UNITED STATES PATENT OFFICE

PHILIP A. KOEHRING, OF MILWAUKEE, WISCONSIN, ASSIGNOR TO KOEHRING COMPANY, OF MILWAUKEE, WISCONSIN, A CORPORATION

DESIGN FOR A COMBINED CONCRETE-MIXER TRUCK BODY AND FRAME

Application filed March 27, 1926. Serial No. 17,078. Term of patent 14 years.

To all whom it may concern:

Be it known that I, PHILIP A. KOEHRING, a citizen of the United States, residing at Milwaukee, in the county of Milwaukee and State of Wisconsin, have invented a new, original, and ornamental Design for a Combined Concrete-Mixer Truck Body and Frame, of which the following is a specification, reference being had to the accompanying drawing, forming a part thereof, in which:—

In the drawings: Figure 1 is a perspective view of my invention looking toward one end thereof.

Figure 2 is a perspective view of the said design looking from the opposite end thereof.

I claim:

The ornamental design for a combined concrete mixer truck body and frame as shown.

PHILIP A. KOEHRING.
